UNITED STATES PATENT OFFICE.

FRANKLIN E. ARNDT, OF GALION, OHIO.

BURIAL-VAULT.

1,104,604.

Specification of Letters Patent. Patented July 21, 1914.

Application filed April 4, 1914. Serial No. 829,644.

To all whom it may concern:

Be it known that I, FRANKLIN E. ARNDT, a citizen of the United States, residing at Galion, in the county of Crawford and State 5 of Ohio, have invented certain new and useful Improvements in Burial-Vaults, of which the following is a specification.

This invention comprehends certain new and useful improvements in burial vaults 10 and relates particularly to doors or closures therefor of the type designed to prevent surreptitious or unauthorized access to the interior of the vault after the door has once been placed in position and locked.

15 The invention has for one of its primary objects a very simple, durable, and efficient construction of device of this character, the parts of which may be very easily manufactured and assembled and not liable to get 20 out of order.

A further object of the invention is a burial vault door embodying an improved construction and arrangement of locking devices whereby the locking arms or members 25 will, in the operation of the locking devices, have imparted to them not only a movement in an outward or radial direction, but a rocking movement in a plane transverse to the outward or radial movement, 30 so that said members will fulcrum upon the door frame and when moved to their operative positions, will not only serve to prevent the removal or detachment of the door, but will also serve to press the door tightly 35 against the frame so as to produce a hermetically tight seal or joint. And the invention also aims to generally improve devices of this character so as to render them more useful and commercially desirable.

40 With these and other objects in view, as will more fully appear as the description proceeds, my invention consists in certain constructions, arrangements, and combinations of the parts that I shall hereinafter 45 fully describe and claim.

For a full understanding of the invention, reference is to be had to the following description and accompanying drawings, in which,

50 Figure 1 is an inner face view of a vault door constructed in accordance with my invention, the door being shown in place with the body portion of the vault in section; Fig. 2 is a vertical transverse sectional view 55 on the line 2—2 of Fig. 1; and Fig. 3 is a

detail view of the actuating device for the locking members.

Corresponding and like parts are referred to in the following description and designated in all of the views by like reference 60 characters.

Referring to the drawing, the numeral 1 designates the body portion of a vault, the same being of any desired construction or design, within the purview of my invention, and 2 designates the closure or door. The door 2 is formed on its rear face and around its margin with any desired number of apertured ears 3 through which locking fingers 4 extend, said fingers being preferably beveled on their rear edges, as indicated at 4^a whereby they will have a cam effect upon the door when they are forced into engagement with the inner ends of the apertured lugs 3 on the one hand and a 75 bead or flange 5 formed on the door frame, as clearly illustrated in Fig. 2. The fingers 4 are preferably formed as integral parts of locking frames or members 6 of which there are four in the present instance, although it 80 is to be understood that the invention is not limited in this regard. Each of these frames or locking members 6 is formed with an inwardly extending stem or shank 7, said shank passing through and being guided by 85 slotted lugs 8 formed on the rear face of the door 2. Revolvably mounted in the door 2 at the center thereof, is an operating device embodying a disk 9 and a cone-shaped thimble 10 formed therewith and projecting 90 rearwardly therefrom, the disk preferably bearing against the rear face of the door and the thimble 10, the larger end of which is rearmost, being formed on its outer surface with a spiral groove 11, the convolutions of which increase rearwardly in diameter, as is manifest. The said actuating device also includes a collar 12 which projects forwardly through an opening formed in the door and which is provided with a 100 non-circular socket 13 for a wrench or crank handle, whereby the said actuating device may be turned. This socket is preferably closed by means of a screw cap 14.

Preferably, coiled expansion springs 15 105 act against the locking members 6 with a tendency to move said members inward and to hold the inner ends of the shanks or stems at all times in proper position within the spiral groove, the springs being pref- 110

erably held in place by nipples 16 formed on the locking members and by lugs 17 formed on the rear face of the door. If desired, the door may be formed on its rear face with other lugs 18 designed to engage the locking members when the latter are in their inoperative or withdrawn positions, said lugs acting in the nature of supports or bearings for the outer ends of the locking members.

From the foregoing description, in connection with the accompanying drawing, the operation of my improved door or closure for burial vaults will be apparent. In the practical use of the device, after the door has been placed in position, the actuating device is rotated in a direction to cause the inner ends of the shanks 7 of the locking members 6 to ride upon the gradually increasing spiral groove 11 formed in the outer surface of the cone-shaped thimble 10, this operation not only producing an outward movement of the locking members into engagement with the inner edge of the flange or bead 5 of the door frame, but also producing a rocking movement of the locking members, whereby they will act in the nature of levers with the bead 5 as the fulcrum and the inner ends of the apertured ears 3 as the parts directly acted upon, and consequently not only will the door be securely prevented from being removed or detached, but it will be tightly pressed against the door frame and produce an air and water tight joint, particularly if a lead or other gasket or packing is interposed between the door and the frame. This is one of the important features of my invention and it will be at once seen that it is an advantageous result which is very readily accomplished.

In order to prevent the door from becoming unlocked after it has once been secured in place, the disk 9 is formed on its periph-

ery with ratchet teeth 19 designed for engagement by a spring pressed locking pawl 20. This pawl may be easily held in the inoperative position illustrated in dotted lines in Fig. 1 so that the door locking devices may be easily manipulated until the time comes when it is desired to finally seal the vault.

While the accompanying drawing illustrates what I believe to be the preferred embodiment of my invention, it will be understood that the invention is not limited thereto, but that various changes may be made in the construction, arrangement, and proportions of the parts, without departing from the scope of the invention, as defined in the appended claims.

What is claimed is:

1. A vault door, a plurality of locking members movably mounted on the inner face of the door, means for guiding the locking members in their movements, and an actuating device revolubly mounted upon the door and operable from the outer face thereof, said actuating device being formed with a spiral groove having its convolutions increasing in a rearward direction and engaged by the locking members.

2. A vault door, a plurality of locking members movably mounted on the inner face thereof, and means operatively connected to said locking members and operable from the outer face of the door for imparting a compound movement to said locking members, to wit, a movement in a plane parallel to the plane of the door, and simultaneously therewith, a rocking movement in a plane transverse to the plane of the door.

In testimony whereof I affix my signature in presence of two witnesses.

FRANKLIN E. ARNDT.
